(57) **CLAIM**

The ornamental design for a cautery device, as shown and described.

DESCRIPTION

FIG. 1 is a front perspective view of the cautery device of our new design;

FIG. 2 is a top plan view of the cautery device of our new design;

FIG. 3 is a bottom plan view of the cautery device of our new design;

FIG. 4 is a right side view of the cautery device of our new design;

FIG. 5 is a left side view of the cautery device of our new design;

FIG. 6 is a front end view of the cautery device of our new design; and,

FIG. 7 is a rear end view of the cautery device of our new design.

The broken line showing is for illustrative purposes only and forms no part of the claimed design.

1 Claim, 6 Drawing Sheets
